ELECTRIC DRY SHAVER

Irving Florman, New York, N. Y.

Application May 27, 1936, Serial No. 82,106

6 Claims. (Cl. 30—43)

My invention relates to shaving devices and more particularly to an electrically driven dry shaver.

A type of dry shaver is well known which consists of a long casing member adapted to be gripped in the hand and having at its end reciprocating blade devices for cutting the beard. Such devices are unsatisfactory inasmuch as in their operation they must be held in a somewhat awkward position. The awkwardness of the position and the tight grip necessary in the use of such arrangements makes the fingers and the hand stiff and makes it difficult to manipulate these devices. Furthermore, such arrangements are difficult to handle where all different points of the face are to be reached. It also generally requires a considerable period of time to learn their proper operation.

A further disadvantage of these devices lies in their expense and complicated construction.

Furthermore, the razors now on the market require the use of a thumb wheel to impart a starting motion to the motor. The arrangements make a considerable amount of noise, and cause rapid interruptions of the electric current which produce disturbances in neighboring electric circuits, thereby causing difficulties in radio reception.

The object of the present invention is to provide an arrangement which overcomes the above disadvantages. Primarily, I desire to provide a device which can be comfortably and conveniently held in the hand in such a position that shaving may be accomplished without any strain or unnatural positioning of the hand. Such an arrangement makes it possible to shave without physical strain and to reach any desired part of the body with the razor. The manipulation of the razor is so simple that no experience in operating the same is necessary.

This purpose is accomplished primarily by arranging the driving motor in a casing of proper width to be gripped in the hand, and preferably substantially square, and positioning the cutting members at the side instead of at the end of the casing.

A further object of my invention is to provide a razor of this type using a shaded pole induction type motor which is noiseless, which runs smoothly, and which starts of itself as soon as the current is applied. By the use of such a motor the device runs more quietly and does not interfere with any other electrical circuits.

Finally, I wish to provide a device which is inexpensive and easy to manufacture, and is

formed of the smallest possible number of parts, so that the device is within the reach of the average user.

Further objects and advantages of the invention will appear more fully from the following description, particularly when taken in conjunction with the accompanying drawings which form a part thereof.

In the drawings:

Fig. 1 is a perspective view of my device 10 showing it held in the hand of the user.

Fig. 2 is a rear view of the same.

Fig. 3 is a front view of the device with the cutting unit and front casing removed.

Fig. 4 is a similar view with the front casing 15 section in position.

Fig. 5 is a bottom plan view of the shaving unit.

Figs. 6 and 7 are cross sections on the lines 8—6 and 7—7 respectively of Fig. 2.

Fig. 8 is a rear elevation of the stationary cutting element. 20

Fig. 9 is a cross section on the line 9—9 of Fig. 7.

Fig. 10 is an enlarged front elevation of the end of the rotor shaft. 25

The arrangement consists essentially of a casing A, for holding the driving unit or motor and a cutting unit B. The casing A is preferably substantially square in cross section, as shown, and the cutting unit B is mounted on, and preferably near the edge of, one of the square sides. Obviously the shape of the casing may be varied considerably. It should, however, be of such a dimension in a direction parallel to the direction of movement of the cutting members as to be readily gripped in the hand. Its dimension perpendicular to the cutting plane of the cutting unit should be relatively small, preferably not exceeding about 1½ inches, and this should be no greater than either of its other dimensions. 30 Furthermore, in the preferred form the two dimensions in a plane parallel to the cutting plane, or in other words the dimensions of the wall which carries the cutting unit, should be substantially equal. 35

As shown in the drawings, the device comprises a casing formed of a front section 2 and a rear section 4 adapted to be connected and held together by screws 6. These members thus form a casing having square front and rear walls 3 and 5. Within this casing is mounted a shaded pole induction motor. This motor comprises a closed magnet 8 formed of laminated blades each in the shape of a ring. Around one portion of the ring is wound a magnet coil 10 connected by 40 45 50 55

a cable 12 to a plug 14 which can be inserted into any alternating current source outlet. The opposed portion of the magnet is provided with an opening 16 in which is arranged the rotor 18 of 5 the motor.

It will be noted that the casing sections are provided with bulging portions 20 within which the coil 10 fits when the device is assembled.

Mounted on opposite sides of the armature are 10 two plates 22 which support bearings 24 in which is rotatably mounted the rotor shaft 26. The rear bearing fits in an opening 28 in the rear casing section 4, while the front bearing extends into an opening 30 in the front casing section 2.

15 The front casing section also has a projecting portion 32 preferably formed integral therewith. This portion terminates in two parallel spaced walls 34 forming between them a slot or groove 36 open at its ends. As will be seen, this slot is 20 adjacent and parallel to one of the edges of the square front wall 3. A ridge 38 is formed in the bottom of this groove and transversely thereof, for a purpose to be explained later.

On the end of the rotor shaft 26 and eccentric 25 thereto is a pin 40 on which is rotatably mounted a sleeve 42. This pin and sleeve act as a crank.

The cutting element is shown in Figs. 5 to 9. It consists of a fixed section 44 and a reciprocating section 46. The fixed section consists of a 30 supporting or base block 48 and a cylindrical portion 50. The cylindrical portion is extremely thin opposite the fixed block 48 and is provided with a series of transverse slots 52 therein.

Mounted in the block 48 and extending within 35 the cylindrical portion 50 are guide members which are threaded in the bottom of the block and are adjustable vertically therein. These members consist of sleeves 51 threadedly adjustable in the base block 48 and having at their outer 40 ends guide slots 53. Pins or rollers 54 are mounted in longitudinal slots 55 in the walls of the sleeves 51, so that the rollers extend perpendicular to the slots 53. A plug 56 is threaded in the rear end of each sleeve, and makes it possible to 45 adjust a coil spring 57 to vary the pressure exerted thereby on rollers 54. The sliding member 46 has extending along one side thereof a rib 58 capable of fitting in the grooves 53. The opposite portion of the sliding cutter member fits 50 tightly against the rear, lower or inner face of the stationary member 44. This is also provided with a series of transverse slots 62, parallel to the slots 52.

It is evident that if the cutting mechanism 55 above described is moved across the face in the direction of the slots, or transverse to the length of the cutting member, and the inner blade is reciprocated, the hairs will pass through the slots of the outer blades, and the reciprocations of the 60 inner blade past these slots will cut the hair and remove the same.

The motor shaft 26 extends through an opening 64 in the base block 48 and the sleeve 42 engages in a cutaway portion 60 of the rib 58. It 65 is evident that when the motor rotates and drives the shaft the eccentric mounting of the pin 40 will cause a reciprocatory motion to be imparted to the movable cutting element 46. By pressing the device against the face, the beard or other hair 70 will be removed.

In order to hold the cutting element in position on the razor, and to prevent removal or loss of the same, the base block 48 is provided with a notch 66 which fits over the ridge 38. A screw 68 75 threaded in one of the walls 34 is adapted to en-

gage a recess 70 in the block 48 and thus hold the cutting element in position. It is quite a simple matter, however, to remove the cutting element for cleaning the same by merely loosening the screw 68.

When a razor of this type is used on the face, 5 it must be pressed fairly tightly in order to cut satisfactorily. This tends to press the skin onto the slots and leave ribs or grooves on the surface of the skin. With this razor it is possible 10 to follow the movement of the cutter with the thumb or one of the fingers tending thus to smooth out and eliminate the effects of the shaving member.

Instead of making the members 46 and 50 of a 15 single piece of metal, as shown, the parts in which the slots are formed may be stamped out of flat spring steel. The non-slotted portions may then be die cast, and the slotted portions fastened to the die cast parts. Such an arrangement could 20 be made more economically than the structure above described.

While I have used in the specification and 25 claims the term "cutting plane of the movable cutting members", I mean a plane substantially tangent to the faces of the cutting members which are provided with the slots, or in other words a plane which substantially represents the plane 30 of the surface of the skin when the razor is in use.

While I have described herein some embodiments 35 of my invention, I wish it to be understood that I do not intend to limit myself thereby except within the scope of the appended claims.

I claim:

1. An electric dry shaving device comprising 40 a casing having substantially square front and rear walls and having a thickness less than either of the dimensions of the front and rear walls, the dimensions of said device being such as to permit the same to be substantially confined within 45 in the hand of the operator, a cutting arrangement including a pair of relatively movable cutting elements mounted on the front wall of the casing and extending therefrom, the cutting plane of said cutting elements being substantially perpendicular to the least dimension of the casing, said cutting elements extending in a direction perpendicular to the least dimension of 50 the casing and parallel to the wall on which they are mounted.

2. An electric dry shaving device comprising 55 a casing having substantially square front and rear walls and having a thickness less than either of the dimensions of the front and rear walls, the dimensions of said device being such as to permit the same to be substantially confined within 60 the hand of the operator, a cutting arrangement including a pair of relatively movable cutting elements mounted on the front wall of the casing and extending therefrom, the cutting plane of 65 said cutting elements being substantially perpendicular to the least dimension of the casing, an electric motor mounted within said casing, and means connecting the motor to the cutting elements to drive the same, said cutting elements extending in a direction perpendicular to the least dimension of the casing and parallel to the wall on which they are mounted.

3. An electric dry shaving device comprising 70 a casing having substantially square front and rear walls and having a thickness less than either of the dimensions of the front and rear walls, the dimensions of said device being such as to permit the same to be substantially confined within 75 the hand of the operator, a cutting arrangement in-

- cluding a pair of relatively movable cutting elements mounted on the front wall of the casing adjacent one edge thereof and extending laterally therefrom, the cutting plane of said cutting elements being substantially parallel to the plane of the front wall, said cutting elements including a stationary element and an element reciprocable in a direction parallel to the adjacent edge, an electric motor mounted within said 10 casing, said motor having a rotor and means to cause rotation of said rotor, a shaft for supporting said rotor and driven thereby, said shaft extending perpendicular to the cutting plane of the cutting elements, and means connecting the 15 shaft to the reciprocable cutting element to drive the same.
4. An electric dry shaving device comprising a casing having front and rear walls of substantially equal dimensions in the planes of the walls 20 and having a thickness less than either of the dimensions of the front and rear walls, the dimensions of said said device being such as to permit the same to be substantially confined within the hand of the operator, the front wall 25 of said casing having a projection extending therefrom adjacent one edge thereof and in a direction perpendicular thereto, said projection having spaced walls parallel to the adjacent edge extending perpendicular to the plane of the front 30 wall, a shaving element mounted between said parallel walls and having a movable cutting element extending in a direction longitudinally of said parallel walls, an electric motor mounted in said casing, and means connecting said motor 35 with said movable cutting element to reciprocate the same.
5. An electric dry shaving device comprising a casing having substantially square front and rear walls and having a thickness less than either 40 of the dimensions of the front and rear walls, the front wall of said casing having a projection extending therefrom adjacent one edge thereof and in a direction perpendicular thereto, said projection having spaced walls parallel to the adjacent edge extending perpendicular to the plane 45 of the front wall and forming a groove there-
- between, a shaving element comprising a base block mounted between said parallel walls, said base block having an opening therein, said base block having a face engaging cutting portion provided with slots therein arranged in a plane substantially parallel to the plane of the side wall and extending in a direction perpendicular to the planes of said spaced walls, a movable cutting element mounted in said first cutting element for movement in a direction longitudinally 10 thereof and transversely of said slots, said movable cutting element having a cutting portion arranged in engagement with the rear face of the cutting portion of the fixed cutting element and having slots therein parallel to the first said 15 slots, an electric motor of the shaded pole induction type mounted in said casing, said motor comprising a magnet frame of substantially ring-shaped section, a coil surrounding one part of said frame, means to connect said coil to a source 20 of current, a shaft mounted in said magnet frame perpendicular to the plane of the front wall of the casing, a rotor mounted on said shaft to be driven by said magnet, said shaft extending through said casing wall projection and said 25 opening in said base block, a pin on the end of said shaft eccentric with respect thereto, and a sleeve rotatably mounted on said pin, said movable cutting element having an opening in the bottom thereof, said sleeve engaging in said opening, whereby upon driving of said motor said 30 movable shaving element is reciprocated with respect to the fixed shaving element.
6. An electric dry shaving device comprising a casing having substantially square front and 35 rear walls and having a thickness less than either of the dimensions of the front and rear walls, the dimensions of said device being such as to permit the same to be substantially confined within the hand of the operator, a shaving unit mounted on the front wall of the casing and extending forwardly therefrom and within the projection of said wall, the cutting plane of said shaving unit being substantially parallel to the front 40 wall of the casing.

IRVING FLORMAN.
